LOUIS A. SCHMIDT, OF NEW YORK, N. Y., ASSIGNOR TO R. HOE AND CO., OF NEW YORK,
N. Y., A CORPORATION OF NEW YORK.

COUNTING-DELIVERY FOR PRINTING AND SIMILAR MACHINES.

1,085,226.

Specification of Letters Patent.

Patented Jan. 27, 1914.

Application filed April 3, 1911. Serial No. 618,527.

To all whom it may concern:

Be it known that I, LOUIS A. SCHMIDT, a citizen of the United States, residing at New York, county of Kings, and State of New York, have invented certain new and useful Improvements in Counting-Deliveries for Printing and Similar Machines, fully described and represented in the following specification and the accompanying drawings, forming a part of the same.

This invention relates to improvements in counting deliveries for printing and similar machines.

In machines for handling and delivering sheets or papers, such, for instance, as printing machines of the fast running web type, the papers are ordinarily delivered to a traveling receiver, such, for instance, as a series of belts. To facilitate the subsequent handling of the papers it is desirable to separate the papers on the receiver in such a way that they may be removed from the receiver in predetermined lots. This separation into lots is usually effected by 20 placing a paper after a predetermined number have been delivered to the receiver, the usual method being to cause the paper to be thrown forward so that it projects considerably beyond the rest of the papers. There is, however, liability that this marking paper may become displaced, so that the 25 papers will not be properly separated when removed from the receiver.

The present invention has for its object to produce an improved counting or indicating delivery for printing or other similar machines in which the papers or similar product shall be automatically bunched or arranged in packs containing a predetermined number.

With this and other objects not specifically referred to in view, the invention consists in certain constructions, and in certain parts, improvements and combinations as 45 will be hereinafter fully described and then specifically pointed out.

Referring to the drawings, Figure 1 illustrates in front elevation so much of a delivery mechanism as is necessary to an understanding of the invention. Fig. 2 is a side elevation, partly in section, of the construction illustrated in Fig. 1.

Referring to the accompanying drawings, as the invention is particularly applicable 55 for use in printing machines, it is shown in

connection with a printing machine delivery, although it may be used with other machines.

Machines embodying the invention will include a receiver for the papers or other product, which receiver may be of any suitable construction, but, in the best constructions, it will be of the traveling type. In the construction illustrated, the receiver comprises a plurality of belts or tapes 1, supported by pulleys 2, mounted on a shaft 3. Constructions embodying the invention will also include suitable means for delivering the papers or other product to the receiver.

While the details of this delivery mechanism may be varied, in the particular construction shown, the delivery mechanism includes a rotating fly, the blades of which are marked 4, this fly being mounted on a shaft 5, the construction being a well-known one in printing machines. In the construction illustrated, the papers are received from a folding cylinder diagrammatically indicated at 6, and after passing through a pair of folding rolls 7, the papers drop on the blades 4, being guided in their movement by guides 8, as is usual in such constructions. These guides 8 have their lower portions bent backwardly, as indicated at 9, so as to cause the papers to be properly delivered to the receiver and to insure their clearance from the blades of the fan.

Machines embodying the invention will include means for bunching papers or other product on the receiver after a predetermined number has been delivered thereto. As illustrated, there is provided a pair of bunching or pusher fingers 10. These fingers are carried on blocks 11 which are pivoted on studs 12 projecting from bracket arms 13. These bracket arms are the arms which support the guides 8, and it will be observed that the pivot points of the bunching or pusher fingers are located within the circumference described by the ends of the fly fingers, so that the pivoted fingers act as extensions of the guides 8 and assist in controlling the papers on the fly and delivering them. These pusher fingers, when this form of bunching mechanism is employed, may be actuated in any suitable way. In the particular construction illustrated, the blocks 11 are connected by rods 14 to arms 15 mounted on a rock-shaft 16. This rock-shaft is provided with an actuating arm 17 which, in

the construction shown, has a cam roll 18 mounted thereon. In the particular construction illustrated, this roll 18 co-operates with a rotating actuator 19 having a notch 5 at 20 in the circumference thereof. This actuator, when it is constructed in the manner described, and as in the construction shown, may be mounted on the shaft 3, as this shaft runs at a lower speed than the fly 10 shaft. In the particular construction illustrated, this shaft 3 is driven by bevel gears 21, 22, the gear 22 being fast to a worm shaft provided with a worm gear 23 meshing with a worm 24 on the fly-shaft 5.

15 The arm 17 before referred to may be provided with a spring rod construction of the ordinary type to cause the roll 18 to follow closely the circumference of the rotating actuator.

20 The gearing by which the actuator shaft is driven will be such as to cause the actuator to effect the operation of the pusher after a predetermined number of papers have been delivered to the receiver and the gearing 25 will, of course, be varied according to the particular number desired. When, however, the roll 18 drops into the notch 20 in the actuator disk, in the construction shown, the pusher fingers will move into the position 30 shown in full lines in Fig. 2, and sweep the papers on the receiver into a pack. On the further movement of the actuator, the roll 18 passes out of the notch and the pusher fingers will be withdrawn into the position 35 shown in dotted lines in Fig. 2, thus permitting the papers to fall upon the receiver. They will fall in an overlapped or fanned-out condition until a predetermined number

of papers have been delivered, when the pusher fingers will again come into action 40 and sweep the fanned-out papers together into a bunch or pack. It will be seen that by thus arranging the papers on the receiver in bunches or packs containing a predetermined number of papers the subsequent 45 handling of the papers will be greatly facilitated.

Changes and variations may be made in the construction by which the invention claimed is carried into effect. It will be understood, therefore, that the invention claimed is not to be confined to the particular construction herein shown and described.

What is claimed is:—

In a counting delivery, the combination 55 with a receiver, of a rotating fly for delivering papers thereto, a shaft on which the fly is mounted, a rotating actuator, an actuator shaft, gearing for rotating the actuator shaft at lesser speed than the fly shaft whereby 60 the actuator is brought into operation after a predetermined number of revolutions of the fly shaft, a rock shaft controlled from the actuator, a set of pivoted pusher fingers arranged to engage the papers on the receiver, the pivots of the fingers being located 65 within the circumference described by the ends of the fly fingers, and connections between the pusher fingers and the rock-shaft.

In testimony whereof, I have hereunto 70 set my hand, in the presence of two subscribing witnesses.

LOUIS A. SCHMIDT.
